HENRY A. WISE WOOD, OF NEW YORK N. Y., ASSIGNOR TO WOOD NEWSPAPER MANUFACTURERY CORPORATION, OF NEW YORK, N. Y., A CORPORATION OF VIRGINIA.

DOUBLE-DECK PRINTING PRESS.

Application filed December 29, 1928. Serial No. 157,711.

REISSUED

This invention relates to a printing press in which there is one deck located above another. The principal objects of the invention are to provide a novel arrangement 5 for the upper decks for the purpose of economizing in the space required for the web supply roll mechanisms and enabling them to be located in a more convenient and available place than has been the case heretofore and at the same time leading the webs to the upper decks without changing their direction and in a short path; also to avoid the necessity of locating the supply roll mechanism at the end of the series of decks 10 of the press and to avoid the running of these webs throughout substantially the whole length of the press before they come to their printing units.

Other objects and advantages of the invention will appear hereinafter.

Reference is to be had to the accompanying drawings in which

Fig. 1 is a side view of a printing press having a plurality of units located above the lower deck and arranged according to this invention;

Fig. 2 is a plan of the same; and

Fig. 3 is an end view of the press showing also the path of the web from the supply 30 roll to the upper deck.

Printing press units are arranged, if possible, on the floor level, one beside another with a paper supply directly underneath them on a lower level, ordinarily called the reel loom. When an additional unit is required and there is no more floor room for 35 it, it is common to place it upon one of the existing units.

On account of lack of space it is becoming 40 more and more necessary to mount upper units upon the ordinary ones at the floor level. As the reason for doing this is the lack of room in a longitudinal direction in a plant, it is obvious that there is little or 45 no room at the end of the plant for the additional paper reels. The ordinary way of mounting the superimposed unit in parallel relationship to the units of the lower deck has ordinarily suggested nothing but the 50 idea of putting the extra paper reels for the upper deck parallel with the paper reels for the lower deck and at the end of the remote machine. This necessitated the bringing of the web to an upper deck all the way 55 from the end of the press. As these upper

decks are naturally put as close as possible to the folding mechanism, this necessitated the guiding of the web throughout substantially the whole length of the press and the crowding of the web supply roll reel for an 60 upper deck into a space entirely inadequate for it. The further expansion of presses in this way necessitates additional units on top of the usual lower level deck.

I have provided a novel arrangement for 65 feeding a plurality of upper decks without carrying the paper all the way through or over the several units and place the web reels within the longitudinal dimension of the plant. In this case, three lower units 70 U are indicated at the floor level, arranged in line as usual, to form the lower deck. The three reels R for carrying the web rolls for supplying the web are indicated in their usual positions. On the frame of the machine above the units U are placed two units U² of the upper deck. In this case each upper unit U² is turned around with the axes of its printing couple at right angles to those of the printing units of the lower deck. I have provided a reel R' for supplying 75 each upper deck U² at the side of the press with the axes of the rolls arranged longitudinal with respect to the length of the press, or at right angles to the usual construction. This enables me to put these reels, or whatever supports are used, at the side of one of the reels R as shown more clearly in Fig. 2. The web is then run upwardly at the side as indicated in Fig. 3. Each web 80 passes over guide rolls 10 and directly into its unit U² without being turned. This provides a very simple way of feeding the web. Each web from these reels R' can be carried 85 up directly at the side without turning and into the units U² and all the way through them in the simplest manner possible. After passing through the upper units U², the webs have to be turned over turning bars 14 before being brought into the folder F. These 90 turning bars of course bring the upper webs over the other webs and in register with them so that they will go into the folder 95 with them.

This shortens the web path from the running web roll to the upper deck and that 100 without hindering the way in which the web is finally delivered from that unit or deck to the folder. In addition to the fact that it shortens the length of the web path, it, of 105 110

course, necessitates more space at the side for the extra reel R'. That space, however, is more apt to be available than further space at the end.

5 It will be understood of course that, although I have illustrated and described only a single type of press, this invention is independent of any particular type of newspaper printing press and can be used generally in 10 the newspaper industry. Although I have illustrated and described only one form of the invention I am aware of the fact that modifications can be made therein by any person skilled in the art without departing 15 from the scope of the invention as expressed in the claims. Therefore, I do not wish to be limited to the details of construction herein shown and described, but what I do claim is:—

- 20 1. In a newspaper printing machine, the combination with a plurality of units on a level constituting a lower deck of a plurality of units above them constituting an upper deck, each of the upper deck units being located with its printing and impression cylinders at right angles to the corresponding cylinders of the lower deck.
- 25 2. In a newspaper printing machine, the combination with a plurality of units on a level constituting a lower deck of a plurality of units above them constituting an upper deck, each of the upper deck units being located with its printing and impression cylinders at right angles to the corresponding cylinders of the lower deck, means for supporting the web supply rolls for the upper

deck with their axes transverse to the axes of the web supply rolls of the lower deck, and means for guiding said web directly into the upper deck to be perfected therein.

40

3. In a newspaper printing machine, the combination with a printing press comprising a series of units on a level constituting a lower deck and a unit above them located with its printing and impression cylinders at right angles to the corresponding cylinders of the lower deck, means for supporting a web supply roll with its axis transverse to the axis of the web supply rolls of the lower deck, means for guiding said web directly into the upper deck to be perfected therein, and turning bars for turning the web from the upper deck into line with the webs delivered from the lower decks, so that it may be received by a folding mechanism located in 50 the proper position for receiving the webs from the units of the lower deck.

55

4. In a newspaper printing machine, the combination with a lower deck, of a plurality of units on a level above them constituting an upper deck, the upper deck being located with its printing and impression cylinders at right angles to the corresponding cylinders of the lower deck, means for supporting a web supply roll for the upper deck with its axis transverse to the axes of a web supply roll of the lower deck, and means for guiding said web directly into the upper deck to be perfected therein.

60

5. In testimony whereof I have hereunto affixed my signature.

HENRY A. WISE WOOD.
